MINING MACHINE

Robert K. Jeffrey, deceased, late of Bexley, Ohio,
by Florence H. C. Jeffrey, executrix, Bexley,
Ohio, assignor, by mesne assignments, to The
Jeffrey Manufacturing Company, a corporation
of Ohio

Application August 10, 1943, Serial No. 498,087

28 Claims. (Cl. 262—30)

1

This invention relates to a mining machine of the type which rests on and slides over the mine bottom and includes rope feeding mechanism, and one of the objects of the invention is the provision of improved and efficient fluid pressure apparatus for controlling the operations of such type of mining machine.

Another object of the invention is the provision of means entirely dependent upon a fluid pressure system for controlling the operations of a mining machine.

A further object of the invention is the provision of means for automatically regulating the feed of a mining machine in accordance with the load thereon by slowing down the feed thereof when hard cutting is encountered and automatically speeding up the feed when normal cutting is resumed.

Another object of the invention is the provision of fluid pressure operated controlling means for a mining machine embodying means for automatically slowing down the feed of the machine when the fluid pressure in the controlling system exceeds a predetermined maximum until such fluid has been reduced and then automatically resuming normal feed.

A further object of the invention is the provision of an electro-magnet in circuit with the electric driving motor of a mining machine and combining with such electro-magnet a fluid pressure control system to effect automatically a slowing down of the feed of the machine when such electric motor is overloaded and then upon the overload being spent restoring the feed to such normal as has been predetermined by the manual setting of a controlling valve.

Another object of the invention is the provision of a supercharging pump of relatively low fluid pressure in a mining machine controlling system embodying a pump of relatively high fluid pressure so as to keep such system filled with oil and displace oil heated during operation of the machine and thereby effect radiation of the heat from the oil and render more uniform the temperature of the oil used in the controlling system.

A further object of the invention is the provision of a variable volume pump and means for controlling the volume of delivery of said pump in accordance with the manual setting of a valve

combined with automatic means for varying the volume of delivery of said pump in compliance with requirements and then restoring the volume of delivery to normal as predetermined by the manual setting of said valve.

Another object of the invention is the provision of an improved hydraulic system of control of the feeding of cutting mechanism of a mining machine wherein a variable volume pump is actuated to establish a normal output as predetermined by the manual setting of a valve and wherein such output is varied in accordance with the load on the cutting mechanism while the feeding of the machine is not interrupted.

A further object of the invention is the provision of fluid pressure controlling means for a variable volume pump to enable the volume of delivery to be predetermined by the manual setting of a valve combined with automatic means for varying the volume of delivery from said pump and then restoring such delivery volume to that predetermined by such manual setting.

Another object of the invention is the provision of hydraulically operated motor means for continuously feeding a mining machine irrespective of varying loads thereon, combined with automatic means for supplying variable volumes of hydraulic liquid to said motor means in accordance with such varying loads, without interrupting the feed of the machine.

A further object of the invention is the provision of an improved automatic suction selector in an automatic hydraulic system of control of a mining machine to adapt the latter for operation on steeply pitched mine veins.

More particularly it is the object of the present invention to provide in that type of mining machine adapted to rest on and slide over a mine bottom, a hydraulic system of control of the feeding of the machine that shall automatically vary the rate of feed of the machine in accordance with the hardness of the material being cut so that when relatively hard material is encountered the feed will slow down automatically and pick up again automatically after normal conditions of operation are resumed, the feeding operation being carried on continuously without stalling the machine.

Other objects of the invention will appear

hereinafter, the novel features and combinations being set forth in the appended claims.

The mining machine shown in the accompanying drawings includes the structure disclosed in applicant's co-pending application, Serial No. 468,398, filed Dec. 9, 1942, for an improvement in Mechanism for removing cuttings from the kerf cutter of a mining machine, now Patent No. 2,359,422, dated October 3, 1944.

In the accompanying drawings,

Fig. 1 is a side elevation of a short wall kerf-cutting mining machine to which my improvements are particularly adapted;

Fig. 2 is a rear end elevational view of the mining machine shown in Fig. 1;

Fig. 3 is a plan view of the mining machine shown in Fig. 1;

Fig. 18 is a sectional elevation of a 3-core differential pressure control valve mechanism;

Fig. 19 is an enlarged sectional elevation of the manually set hydraulically actuated volume control device and balance cylinder shown in Fig. 9;

Fig. 19a is a development of a portion of the interior of a valve sleeve and cooperating valve post;

Fig. 20 is an enlarged sectional elevation of a double check valve for use in supercharging the hydraulic system;

Fig. 21 is a sectional elevation taken on the line 21—21 of Fig. 9, looking in the direction of the arrows;

Fig. 22 is a sectional elevation taken on the

line 22—22 of Fig. 9, looking in the direction of the arrows;

Fig. 23 is a sectional bottom plan view taken on the line 23—23 of Fig. 21, looking upwardly in the direction of the arrows;

Figs. 24 and 25 are left-hand and right-hand sectional views of the supercharging check valve and emergency relief valve combination;

Fig. 26 is a sectional elevation of the trammimg relief valve;

Fig. 27 is a plan view of a shortwall kerf-cutting mining machine mounted on a truck and operatively connected to truck propelling mechanism to transport the machine from one place to another;

Fig. 28 is a sectional elevational view of the power transmission mechanism driven by one of the rotary hydraulic motors and adapted to be connected to the truck propelling mechanism as illustrated in Fig. 27;

Fig. 29 is an enlarged plan view of the rear end portion of the mining machine with the cover removed to show the hydraulic apparatus used in the operation of the power transmission mechanism shown in Fig. 28 when connected to the truck propelling mechanism illustrated in Fig. 27;

Fig. 30 is a rear end view of the structure shown in Fig. 29, with the rear end cover of the main frame removed;

Fig. 31 illustrates diagrammatically the complete hydraulic system of hydraulic circuits and connections for a shortwall kerf-cutting mining machine including provision for transportation truck drive as shown in Fig. 27; and

Fig. 32 is a piping diagram for a shortwall kerf-cutting mining machine without any provision for transportation truck drive.

As shown in Figs. 1 and 3, the chain kerf-cutter 12 comprises a cutter bar 16 which is provided with the conventional endless cutter chain 17 carrying picks or bits 18. The cutter chain 17 is driven from an electric motor carried by the main frame 11 of the mining machine under the cover plate 19 shown in Fig. 3. As indicated in this view and in Fig. 7, the armature shaft of the electric motor is connected to the pinion 20 which meshes with the gear 21 secured to the shaft 31 carrying the worm 22.

The worm 22 meshes with a worm gear 23 as shown in Figs. 3, 4 and 7. This worm gear is mounted on the roller bearing 24 concentric with the vertical shaft 25 to the upper end of which is secured the clutch gear element 26.

Secured to the upper side of the worm gear 23 are splines 27 which mesh with splines on the vertically sliding clutch element 28; the latter has an annular groove 29 to which is connected the shipper 30. By means of the shipper 30 the splines on the clutch element 28 may be slid upwardly into mesh with the gear element 26 and when this occurs the worm gear 23 will be brought into driving relation with the vertical shaft 25, the lower end of which carries the sprocket 31 meshing with the cutter chain 17.

As shown in Fig. 4, the vertical shaft 25 is journaled by means of the opposing roller thrust bearings 32 and 33 to the tubular support 34 which is secured to the frame 11 of the mining machine by means of the cap screws 35, 35. A retaining ring 36 is secured to the tubular support 34 by means of cap screws to hold the thrust bearings 32, 33 in adjusted positions.

The shaft 37 (Fig. 7) which carries the worm 22 is connected to the hydraulic variable volume

pump 64 for supplying hydraulic pressure to the hydraulic motors 65 and 66. The hydraulic motor 65 is connected to a shaft 41 carrying a worm 42 which meshes with a worm wheel 43 as shown in Fig. 4. The worm wheel 43 is keyed to a shaft 44 mounted in journal bearings and secured to a pinion 45 which meshes with an inner annular gear 46 of a rope drum 47. In a similar manner, the rope drum 48 on the opposite side of the machine as shown in Figs. 3 and 7, is connected through worm gearing 49 to the hydraulic motor 66 for operation thereby. The helix angles of the gears 42 and 43 and of the gearing 49 are such that their drives are reversible, that is, gears 42 may drive gears 43 or gears 43 may be caused to drive gears 42.

As best seen in Figs. 5 and 6, secured to the lower edge of a plate 11' of frame 11 is a bracket 230 for carrying the sleeve 231 which has an enlarged cylindrical head 232 fitting into a circular opening at the lower end of the plate 233 and serving to pivot the latter for tilting adjustment. The rope drum 47 is journaled on the stub shaft 234 which is supported by the plate 233.

The upper left-hand portion of the plate 233 is provided with an arm 233' carrying a cup-shaped sleeve 235 in which is slideable a latch 236 adapted to fit into recesses 237, 238 in the plate 11'. The latch 236 is urged against the plate 11' and into the recesses 237, 238 by the spring 239 in the cup 235. A stem 240 connects the latch 236 to the knob or handle 241.

By grasping the knob 241 and pulling the same outwardly the latch 236 may be released and the plate 233 tilted on its cylindrical pivot 232 to throw the pinion 45 into or out of mesh with the inner annular gear 46. The latch 236 may initially be in the recess 237 but when the gears 45, 46 are to be thrown out of mesh with each other to enable a manual pull on the rope 50 to rotate the rope drum 47 freely, the latch is adjusted to the recess 238.

The gears should not be moved too far out of mesh with each other, however, and this is prevented by the screws 242, 243, 244 and 245 each of which extends through a slot in the plate 233 and is screwed into the supporting plate 11'. The slots for the screws 244 and 245 are shown at 246, 247, and this view illustrates the slot 246' for the screw 242 and the slot 247' for the screw 243.

A wire 248 may be extended through holes in the heads of the screws 242, 243 and a wire 249 may be extended through holes in the heads of the screws 244, 245. The ends of the wires may be twisted together as shown in Fig. 5. By soldering these twisted ends the arrangement will be sealed and tampering with the proper support of the rope drum prevented.

In the bearing block 231 is located a brake shoe 250 which is pressed against the rope drum 47 by means of the spring 251 as shown at the lower end of Fig. 6. The stem 252 of the brake shoe extends through the spring 251 and is provided with a transverse slot 253 through which extends a limiting or locking rivet 254 to prevent the brake shoe from dropping out when the plate 233 is removed for repairs or replacements.

It should be understood that when the gears 45, 46 are thrown out of mesh, too free rotation of the rope drum is prevented by the brake shoe 250 frictionally engaging the peripheral portion of the rope drum 47, as shown in Fig. 6.

For normal feeding operation of the kerf-cutter horizontally transversely of itself, a rope 50

is connected to and wound on the drum 47 to extend therefrom around the guide pulley 51, and the rope 52 is connected to and wound on the drum 48 to extend therefrom over the direction pulleys 53, 54. The ends of the ropes are connected to anchorages in the mine and as rope 52 is wound up the other rope 50 is paid out, under control of the hydraulic motors 65 and 66. For haulage purposes when the mining machine is to be moved from place to place in the mine without effecting any feeding operation, the rope 50 may be extended around the direction pulleys 55 and 56 and its free end anchored in the mine distant from the machine. When the pulley 56 is not in use, its supporting arm may be moved to the vertical position shown in full lines in Fig. 3 and held there by a pivoted latch.

It will thus be seen that when the electric motor drives the chain cutter 12, it at the same time drives the shaft 37 which is connected to the variable volume pump 64. This variable volume pump 64 is shown in detail in Figs. 9, 21, 22 and 23. The shaft 68 of this pump is adapted to have its outer extension 37' connected to the shaft 37 (Figs. 3, 7) so as to be in alinement therewith. It should be understood that when the kerf-cutter driving motor operates, the variable volume pump 64 will be driven but the volume of liquid delivered by this pump will vary from zero to a maximum according to the adjusted position of the swash plate 69. When the latter is adjusted to the position shown in Fig. 9, it may be said that it is centered, in which position the pump has zero capacity. The angle of the inclination of the swash plate 69 relative to the axis of rotation of the shaft 68 will determine the capacity of the pump or the volume of its delivery, as hereinafter more fully explained.

While the variable volume pump 64 and the two constant volume fluid pressure motors 65 and 66 are connected in series, these motors are operable singly or in series and each is reversible independently of the other. Therefore, the rope drum 47 may be rotated in either direction by means of its rotary hydraulic motor 65 and the rope drum 48 may be rotated in either direction by means of its hydraulic motor 66. Fig. 16 when considered as a sectional plan view represents a left-hand four-way valve for controlling the rotary hydraulic motor 66 and the same view when considered as a sectional bottom plan view represents a right-hand four-way valve for controlling the rotary hydraulic motor 65 shown in Fig. 3.

A handle 70 connected to the left-hand four-way valve for the motor 66 may be located at the rear end of the machine as shown in Fig. 2. A similar handle 71 may be located as shown in the same view and connected to the right-hand four-way valve for the motor 65.

If the coal to be cut is relatively soft the variable volume pump 64 may be adjusted for maximum delivery which will effect relatively high speeds of rotation of the rope drum motors 65 and 66. But if as the machine is cutting, the feed is set so high as to cause excessive pull on the feed cable 52 there will result a hydraulic pressure overload in the hydraulic system. Or if the kerf-cutter after cutting along through relatively soft coal encounters a hard spot, the cutting motor may be overloaded, in which event the hydraulic system of control illustrated in the accompanying drawings comes into play automatically to decrease the volume of the variable volume pump 64 until the relatively hard ma-

terial has been cut through whereupon the desired rate of feed of the kerf-cutter is automatically resumed.

Within the supporting frame 11 back of the electric chain cutter driving motor are two compartments covered by the plate 72 and entirely closed to form a sump (Fig. 8) for the oil used in the hydraulic control system. There may be two compartments divided by the partition 73 through openings 73' in which the oil may be free to flow from one compartment to the other as shown in Fig. 8 but the enclosure of such compartments is such that the oil can not escape therefrom during normal operation of the mining machine.

The worm gearing 22, 23, 42 and 49 may run in oil in one compartment and the other compartment may serve as the sump or source of supply for the automatic suction selector valve 74 shown in section in Figs. 7, 8 and 17 and diagrammatically in Figs. 31 and 32 in the hydraulic control system. This automatic suction selector valve is so arranged that, regardless of the tilt of the mining machine including the frame 11, oil will be drawn into the pipe 75 by the supercharging pump 67. This supercharging pump is a gear pump designed so that the suction and pressure ports will respectively be the same irrespective of the direction of rotation of the pump.

From the supercharging pump 67 the oil flows through the pipe 76 (see Fig. 32) to and through primary filter 77 into the pipe 78 and from the latter into the lower left-hand port 79 of the double valve 20 shown in detail in Fig. 20.

The pipe 78 has connected thereto the branch pipe 81 which leads to a secondary filter 82. The latter may be provided with a relief valve therein. After passing through the secondary filter 82 the oil flows through the pipe 83 to the top of the gummer shaft 25' (Fig. 32) and thence back to the gear case and oil sump. The quantity of oil flowing to the shaft 25' should be small and is regulated by a restricted orifice in the secondary filter 82.

Another pipe 84 may be connected to the pipe 78 to branch therefrom through the low pressure relief valve 86 into the pipe 87 and thence into the gear case or into the sump.

When the mining machine is cutting from right to left while feed rope 52 is being reeled in and rope 50 paid out, the variable volume pump 64 will be running in a counter-clockwise direction so that pipe 95 is connected to the suction port of the pump and the pressure port of the latter is connected to the supply pipe 97.

The pipe 78 is connected to the chamber 79 in the double check valve 20 shown in Fig. 20. Since the high pressure pipe 98 is connected to the supply pipe 97 and leads to the chamber 88 in the double check valve 20, as shown in Fig. 20, the check valve 89 will be held closed. The supercharged oil enters by way of the chamber 79. This supercharged oil is at a lower pressure than the high pressure oil in the pipe 98 and consequently it is not able to open the valve 88 which remains closed. But the supercharged oil in the chamber 79 has sufficient pressure to open the check valve 89 and flow into the chamber 91 and thence into pipe 94. In this manner the supercharged oil enters the system by way of the suction pipe 95 to the variable volume pump 64, since pipe 96 is connected to the pipe 95 as shown in Fig. 32.

High pressure oil in the supply pipe 97 flows

to the right-hand four way valve 101. When this valve is in its neutral position shown in Fig. 16 the oil under pressure will extend from port 97' to port 102 and thence through the hole 103 to the interior of the hollow valve 104 and along the latter to and through the hole 105 into the port 106' and out from the latter into the pipe 106.

The left-hand valve 107 is illustrated in Fig. 16a. The oil enters the valve 107 from pipe 106 to port 106'' and flows through ports 102, 103, 104 and 105 and finds its way back to the pump through the return pipe 114. The right-hand four-way valve is connected by means of the ports 108, 109 and the pipes 110, 111 to the rotary hydraulic motor 65 as shown in Figs. 16 and 32. The left-hand four-way valve is connected by similar ports and the pipes 112, 113 to the rotary hydraulic motor 66. It is evident from Fig. 16 that when the valve 104 is in neutral position the supply pressure is exerted at both ports of the motor 65 and therefore the latter does not operate. In a similar manner when the valve 107 is in neutral position supply pressures will be exerted in the pipes 112, 113 connected to this valve and therefore the latter will not be rotated. Consequently when both the right-hand four-way valve and the left-hand four-way valve are in their neutral positions neither the motor 65 nor the motor 66 will be operated, but a no-load by-pass will be established between the pressure and suction ports of the variable volume hydraulic pump 64.

Under these conditions the cutter chain 17 may be driven by the motor located under the plate 19. At the same time the supercharging pump 67 may be driven by sprocket chain gearing 332 including the sprocket 115' on the shaft 37 and the sprocket 116' connected to the pump 67 as illustrated in dotted lines in Fig. 3 and in full lines in Fig. 7. That is to say, whenever the mining machine electric motor is operating, both pumps 64 and 67 will be driven, but so long as the valves 101 and 107 remain in their neutral positions the mining machine will not be given any feeding movement because the rotary hydraulic motors 65, 66 will not be driven.

Feeding of the machine may be effected by manually actuating the rods 115, 116 of the valves 101, 107. By moving the rod 115 to the right as viewed in Figs. 30, 31 and 32, high pressure oil is delivered through the port 109 and the pipe 111 to the motor 65 to effect operation of the latter to drive the rope drum 48 to reel in the cable 52. At the same time the rod 116 may be moved to the right to cause supply pressure to be exerted in the pipe 112 and return through the pipe 113 to operate the motor 66 to effect paying out of the retarding rope 50. Inasmuch as the motors 65 and 66 may each be controlled independently of the other, the machine may be retarded by the rope 50 as desired and furthermore the machine may be hauled about in the mine by exerting a pull on the rope 50 particularly when the latter is extending from the pulley 56 and anchored extraneous to the machine.

Branching from the pipe 98 adjacent the valve 101 is a pipe 117 which leads to the central core valve 118 of the three-core differential pressure control 119 shown in Fig. 18. It should therefore be understood that when the mining machine is cutting a kerf from right to left, the core valve 118 is held up since the pipe 117 is being supplied with high pressure oil from the supply port of the pump 64. When the core

valve 118 is thus held up, high pressure oil is delivered through the passageway 120 to the core valve 121.

The pipe 117 is connected to the annular port 222 which is connected through the annular channel 223 to the annular port 224. Ports 225 connect the channel 223 to the bore 226 which extends upwardly to the port 227. When the pressure in the pipe 117 is sufficiently low the passageway 228 will let the core 118 drop into the recess 118'. The port 120 is then cut off from the channel 223 but the port 227 is connected by the dropping of the core 118, to the port 123.

It should also be noted that the core valve 118 is connected by the pipe 122 to the pipe 114 (see Fig. 32) near the valve 107, which pipe 114 in turn communicates with the suction pipe 94. When the valve 118 is up, the pipe 122 is connected through the channel 229 and the passageway 123 to the low pressure relief valve 124. When the valve 118 drops, the connection between the pipe 122 and the relief valve 124 is cut off. The flow of oil into the closed system by way of pipe 95 will then increase.

Either the opening of the electro-magnetic valve shown in Fig. 15 or the opening of the high pressure relief valve 165 shown in Fig. 18 will cause excessive hydraulic pressure on the lower end of the high pressure relief valve 121 to lift the latter against the action of the spring 172. The supply pipe 117 will then be connected to both the pipes 159 and 159'. The connection to the pipe 159' results in the opening of the check valve 170 shown in Fig. 19 with the consequent tilting of the swash plate 69 toward central position thereby reducing the output from the variable volume pump 64 and the reduction in hydraulic pressure in the supply line.

When the hydraulic pressure overload has been spent, the valve 121 is pushed down by the spring 172 as permitted by the restricted passageway 173. The swash plate is then automatically restored to its normal position as predetermined by the setting of the manual valve 138. During this automatic restoration the hydraulic motor 126 predominates while liquid is drained from the volume control device 133 through pipe 159', channels 158, 159 into the pipe 157 and thence into the sump.

It should be particularly noted that if the pressure in the supply line 117 falls unduly, the floating spool 118 will drop down from its position shown in Fig. 18 because of the hydraulic pressure exerted from the supercharging pump 67 through the pipe 122 into channel 229 and thence along the passageway 228 to the closed upper end of the floating spool valve 118. If the pressures on the ends of the valve 118 are approximately the same, the latter acts as a floating valve but when the pressure on the upper end exceeds that on the lower side the spool 118 moves down and becomes a differential valve.

When in its lowermost position the valve 118 cuts off the supply pipe 117 from the passageway 120 and the channel port 169, and the valve 121 remains in its lowermost position shown in Fig. 18. The dropping of the valve 118 also cuts off the pipe 122 from the relief valve 124 while the pipe 117 will be connected through the tubular chamber 226 and the lateral port 227 to the low pressure relief valve 124.

It will thus be seen that when the pressure in the supply pipe 117 falls below a predetermined minimum, the valve 118 will drop to cut off pipe 117 from the pipe 150 and at the same

time flow through the pipe 122 will be cut off at 229 in Fig. 18. Consequently, as may be seen by referring to Fig. 32, the flow from the supercharging pump 67 past the check valve 89 in Fig. 5 will replenish the liquid in the pipes 98, 97 and 117, the outlet for the flowing liquid being past the low pressure relief valve 124 in Fig. 18. This flow from the supercharging pump is in addition to the delivery from the main pump 64 and therefore the pressure in pipe 98 soon builds up until the check valve 89 closes and the check valve 90 opens, whereupon the supercharging pump 67 delivers the fluid into the suction pipe 95. It is during the period when the pumps 64 and 67 are in parallel that normal pressure in 15 the supply pipe 117 is restored so that by the time these pumps are again connected in series, the pressure on the lower end of the valve 118 is sufficient to lift the latter to its position shown 20 in Fig. 18. The pipe 122 will then be again connected to the low pressure relief valve 124 and the port 227 will again be closed. During normal operation the supercharging pump 67 is connected in series with the pump 64 through pipe 25 97, the pipes 114, 122 serving as a by-pass through the low pressure relief valve 124 to the sump.

However, there takes place a constant draining of the liquid pressure medium into the sump in order to keep down the temperature of such liquid pressure medium. This may be understood 30 by considering the valves 101 and 107 in their neutral positions. The flow will then be through the no-load by-passes in the valves 101 and 107. In Fig. 32 the flow may be traced from pump 64 35 through pipe 97, valve 101, pipe 106, valve 107, to pipe 122 and thence through the low pressure relief valve 124 to the sump. When this flow as traced reaches the pipe 114 some liquid may 40 go back to the pipe 95 depending upon the pressure exerted by the supercharging pump 67 in the pipes 94 and 95.

When the valve 118 is in its lowermost position the closure of the ports 120 and 169 locks the liquid in the pipe 150 thereby preventing 45 operation of the hydraulic motor regulating means shown in Fig. 19, until normal pressure has been restored in the supply line 117 and the differential valve 118 has been moved back to its uppermost position shown in Fig. 18.

50 The three core differential pressure control shown in Figs. 18 and 32 determines the supercharging pressure of the circuit. The supercharger circuit extends from pipe 78 through port 79, passageway 92, check valve 90, passageway 91, pipes 94, 114, 122, channel 229, port 123 through 55 channel 93 above relief valve 124 to pipe 125. All supercharging oil in excess of that lost through use or leakage in the system is discharged through pipe 125 as a lubricant over the sprocket shaft 60 25. (Figs. 18, 31 and 32).

In the event of the pressure in pipe 97 dropping, temporarily or otherwise, below the supercharging pressure in the pipe 78, the check valve 89 will automatically open to permit the supercharging pump 67 to build up pressure for flow of oil past the check valve 89 and through the pipe 98 into the supply pipe 97, to keep the circuit filled with liquid until the hydraulic pressure in the system supplied by the variable volume pump 64 is again higher than the hydraulic pressure produced by the supercharging pump 67 in the pipe 78.

The volume of oil delivered by the variable volume pump 64 is regulated by adjusting the angle 75 of tilt of the swash plate 69 (Fig. 9). A hy-

11

draulic motor 126 comprising a cylinder 127 and a plunger 128 is mounted in position to act on the roller 129 as shown in Fig. 9. The hydraulic motor 126 acts as a balancing motor and is always connected to the high pressure side of the circuit as will hereinafter more fully appear.

To the port 130 at the left-hand end of the cylinder 127 is connected a pipe 131. A pipe 132 branches to the left from pipe 131 as shown in Fig. 32. The pipe 132 is connected to the port 132' of the manually set hydraulically actuated volume control device 133 which is shown in sectional elevation in Fig. 19.

The volume control device 133 comprises a casing 134 which is rigidly secured to the base plate 135 to which is also rigidly secured the casing 136 of the pump 64. (Fig. 9). To the outer end of the casing 134 is secured the bearing block 137 in which is journaled the core valve 138. To the outer end of the valve 138 is secured a handle 139 (Fig. 9). By means of the handle 139 the valve 138 may be rotated to various positions to secure adjustment of the tilt of the swash plate 69.

The casing 134 in reality constitutes a hydraulic cylinder because within the same is a piston 140. Extending to the right from the central portion of the piston 140, as viewed in Fig. 9, is a cylinder 141 closed at its right-hand end by the block 142. Extending to the right from the central portion of the casing 134 is a cylinder 143 adapted to act as a tubular guide for the plunger 144 the outer end of which is in engagement with the roller 129' mounted on the swash plate 69 diametrically opposite the roller 129.

The valve 138 is provided with two parallel longitudinal bores 145 and 146, each closed at its ends but each in communication with a pair of spaced lateral ports or passageway 145' and 155, each pair of which is connected by a groove or channel as seen in Figs. 9 and 19. A port 132' communicates with an annular groove 147 in the end block 137. The port 148 at one end of the bore 145 is always in communication with this annular groove 147, as shown in Fig. 19.

High pressure oil delivered to the core valve 121 flows from port 149 through the pipe 150 to the port 130 at the left-hand end of the hydraulic motor 126, as viewed in Fig. 9. The pressure in the cylinder 127 on the plunger 128 tends to tilt the swash plate 69 away from central position, thus increasing the volume of flow from the pump 64. The flow will be at a minimum when the parts occupy the positions shown in Figs. 9 and 19 because the piston 140 is then in its extreme right-hand position where it is locked by the oil confined in chambers 151 and 153 of the volume control device 133. The piston 140 is confined to a rectilinear movement by a spline or key 152 between the cylinder 141 and the tubular guide 143.

Within the cylinder 141 is a spiral groove 153 which extends substantially the full length thereof making one complete convolution and connects the chambers 151 and 154. The separate ports 145' and 155 for the bores 145 and 146, respectively, normally straddle this groove 153 and may selectively be brought into communication with the spiral groove 153 by opposite relative rectilinear or axial movements between sleeve 141 and post 138. When the core valve 138 is turned by means of the handle 139 until the port 155 communicates with the spiral groove 153, the chambers 151 and 154 will be in communication with the port 155 through spiral groove 153 and will be

12

vented through the bore 146, annular groove 156, pipe 150', ports 158, 159 and pipe 157 to the gear case or oil sump. The hydraulic motor 126 then acts to move its plunger 128 outwardly and at the same time due to the venting of the oil through the spiral groove 153 the plunger 144 will be retracted. The tilt of the swash plate 69 will thus be increased to effect an increase in the volume of liquid pumped by the pump 64.

When motor 126 acting through swash plate 69 moves cylinder 141 to such extent that the spiral groove 153 is no longer in communication with the port 155 the pump 64 attains the output volume predetermined by the setting of the core valve 138. That is to say, as the piston 140 moves into the chamber 151, the port 155 moves away from the spiral groove 153 and the flow through the latter is discontinued. The oil in the chambers 154 and 151 again becomes trapped because the vent connections of the chambers which are through spiral groove 153 and ports 155 to the sump are sealed. The swash plate 69 is held at its adjusted angle because plunger 144 can recede no further and motor 126 is always acting to rotate swash plate 69 to apply pressure upon it. Thus the pump is confined to the volume predetermined by the setting of the core valve 138.

Now in order to decrease the volume of the pump 64, that is, to expand the volume control device 133 and to retract the piston 128 of the motor 126, the core valve 138 is rotated until the high pressure oil port 145' is in communication with the spiral groove 153. Then oil under pressure flows through the spiral groove 153 into the chambers 151 and 154 to act on the piston 140 and closure 142. At the same time high pressure oil acts on the plunger 128 of the motor 126, but the combined areas of the piston 140 and closure 142 are greater than the cross-sectional area of the plunger 128. Consequently the plunger 144 will be extended and the plunger 128 will be retracted, thereby effecting tilting of the swash plate 69 toward central position to decrease the volume of the pump 64.

As the piston 140 moves toward the plunger 144, the port 145' will be moved away from the spiral groove 153 and the flow of oil into the chambers 151 and 154 cut off, whereupon the oil in the chambers 151 and 154 will be locked to block the piston 140 against further relative movement in the cylinder 134. The swash plate will thus be locked in adjusted position in accordance with the manual setting of the core valve 138.

Under normal or balanced conditions, as illustrated in Fig. 19a, the ports 155 and 145' straddle spiral groove 153 with ports 155 and 145' so located that as post 138 is rotated from its "full-on" position toward the "full-off" position to decrease the normal pump output, the pressure port 145' moves toward the spiral groove 153 and the exhaust port 155 moves away from said spiral groove.

It will be seen that when the pressure port 145' opens into the spiral groove 153 as a result of such movement, high pressure oil will flow into the chambers 151 and 154 to cause the piston 140 to move upwardly until the sleeve 141 closes the port 141'. Thus the piston 140 will move upwardly as the post 138 is rotated from its "full-on" position toward its "full-off" position. It will also be seen that when high pressure oil enters chambers 141 and 154 through check valve 170, the piston 140 will be moved upwardly even though the port 141' be closed. When this occurs the exhaust port, because of its length, will be placed in communication with the spiral groove 153 but because the

13

passage 146 is also subjected to the pressure of the oil entering the chambers 151 and 154 from pipe 150' it is effectively sealed. When the overload condition in the hydraulic system has been relieved, and consequently the high pressure in pipe 150' removed, the oil in chambers 151 and 154 will flow or be exhausted through the spiral groove 153 and port 155 to the pipe 150' and to the sump, as previously described, to permit the piston 140 to move downwardly until the spiral groove 153 is again straddled by the ports 155 and 145'. A single exception to the above description relating to the communication between the exhaust port 155 and the spiral groove is when the post is set to the "full-off" position. In this setting of the post the exhaust port 155, as viewed in Fig. 19a, is positioned too far to the left and does not meet the spiral groove. This because it is desired to lock the piston in the "full-off" position by closing the exhaust port 155. The maximum angle through which post 138 can be rotated from the "full-on" to the "full-off" or minimum positions is preferably not over 180 degrees. The spiral groove 153 extends preferably through an angle of 360 degrees but not more. As viewed in Fig. 19a, the pressure port 145' will be just below and near the top of the groove 153 when the post 138 is in the "full-on" position.

It should be particularly noted that Fig. 18 is a sectional elevation of three core differential pressure control valve mechanism for use in the hydraulic systems of Figs. 31 and 32 in controlling the maximum pressure oil of the supercharging and high pressure circuits.

The valve mechanism shown in Fig. 18 is so located in Figs. 31 and 32 in the hydraulic circuits that it will be possible to separate the low pressure supercharging oil from that of the high pressure oil.

In Fig. 18 the center core valve 118 may be considered a floating spool which is controlled by the high pressure oil being delivered through the pipe 117 and the low pressure oil being delivered through the pipe 122. When high pressure oil is being delivered through pipe 117 into port 222, it passes by way of the annular channel 222 and ports 225 into the core 226 of the valve 118.

The low pressure oil flows from pipe 122 into the annular channel 229 and thence through the tubular passageway 228 to the upper end of the valve 118. Since high pressure oil is exerting its pressure on the underside of the valve 118 and low pressure oil is exerting its pressure on the upper side of the valve 118, the latter will be held in its uppermost position as shown in Fig. 18. If the pressures in the pipes 117 and 122 were reversed, the greater oil pressure would be on the upper side of the valve 118, and the valve 118 would be forced down to its lowermost position.

The right-hand core valve 121 of the three core valve mechanism shown in Fig. 18, is the high pressure relief valve and the left-hand core valve 124 is the low pressure relief valve. So long as the central core valve 118 is held in its uppermost position shown in Fig. 18, high pressure oil will always be delivered to the high pressure relief valve 121 through the port 120 while low pressure oil is being delivered to the low pressure relief valve 124 through the port 123.

The high pressure oil that is delivered to the high pressure relief valve 121 may flow from the annular channel 139 through the radial ports 138 into the lower chamber 197. From the chamber 197 the oil may flow through the vertical re-

14

stricted passageway 173 into the bored recess 198 in which the restoring spring 172 is located. Since the oil pressure extends to both ends of the core valve 121 the pressure on the latter will be equalized thereby permitting the spring 172 to hold the valve 121 in its lowermost position as shown in Fig. 18. This spring 172 is of just sufficient strength to hold the valve 121 in its lowermost position so long as the hydraulic pressure in pipe 117 does not exceed a predetermined normal maximum.

Excessive pull on the feed cable 52 may take place, whereby a pressure overload may occur. For instance, if during cutting, harder coal than usual is encountered, the motor 66 will be called upon to do more work. The volume from the pump 64 remains constant for a given setting of the valve 138 of the volume control device 133, but the heavier duty thrown on the motor 66 increases the pressure in the system.

In case of such high pressure overload due to excessive cable pull, the spring loaded ball check valve 165 (Fig. 18) will be opened to effect by-passing of the oil from upper side of the valve 121 faster than it can enter through the restricted orifice 173 in the center of the valve 121, causing a pressure differential between the top area and the bottom area of the valve 121 of sufficient magnitude to lift the valve 121 against the downward action of the spring 172. It should be understood that the port 168 in Fig. 18 affords free communication between the chamber 167 and the port or passageway 195. It should also be noted that when such high pressure overload takes place, it is extended to the pipe 117 and to the chamber 197 at the lower end of the valve 121 and that when the check valve 165 opens as above explained, escape of oil through the pipe 194 is cut off by the closure at this time of the port 190 by the valve 168 as illustrated in Fig. 15 and as more fully explained hereinafter.

The oil that flows past the check valve 165 escapes through the port 168 and the low pressure relief valve 124 to the pipe 125 and then to the top of the sprocket shaft 25. It will thus be seen that since escape through the pipe 194 is cut off and the pressure at the bottom of the valve 121 is sufficient to overcome the spring 172, the valve 121 is moved up and such upward movement forces the oil out of the chamber 167 through the port 168 into the passageway 195, producing enough hydraulic pressure in the latter to effect opening of the check valve 165.

When the valve 121 is in its raised position, the port 168 is in communication with the port 158. High pressure oil from the pipe 117 will then be delivered to the pipe 150'. Consequently, as shown in Fig. 19, oil will flow from the annular channel 156 past the check valve 170 and through the passageway 171 into the chamber 151. From the chamber 151 the oil will flow through the spiral groove 153 into the chamber 154.

Consequently, hydraulic pressure will be exerted on both the bottom of the closure block 142 and the bottom of the piston 140. This will cause tilting of the swash plate 69 toward its central or "full-off" position, thereby decreasing the output volume of the pump 64. Under these conditions, port 155 will communicate with groove 153 regardless of the manual setting of post 138, except in case it is also in the "full-off" position. Consequently when normal conditions are restored in the hydraulic circuit and the pressure in pipe 150' is reduced or released the pump 64 will automatically return to its normal prede-

terminated position as determined by the position of adjustable post 138.

The high pressure core valve 121 is also provided with four circumferentially spaced vertical V-slots 200 to effect a metered or throttled flow action on the automatic swash plate centering mechanism shown in Fig. 19. That is to say, when the valve 121 is moved up, the V-slots 200 will effect a gradual opening of the communication between the port 169 and the port 158 and thereby effect a gradual increase in flow into the chambers 151 and 154 of the volume control device shown in Fig. 19. The V-slots 200 will thus prevent chattering in the structure shown in Figs. 9 and 19.

After the pressure overload has been spent, the spring 172 is able again to restore the valve 121 to its lowermost position, the oil flowing upwardly through the orifice 173 to fill the chamber 167 while the check valve 165 remains closed. The port 169 will be cut off from port 158 and the latter will be connected to the port 159 as shown in Fig. 18.

It is therefore evident that when the valve 121 is restored to its lowermost position, as shown in Fig. 18, the pipe 150' will be vented through pipe 157 for flow of oil from the pipe 150' to the oil sump. The hydraulic pressures on the block 142 and the piston 140 are therefore relieved while the hydraulic pressure on the plunger 128 is retained.

When a high pressure overload due to excessive cable pull occurs, the tilting of the swash plate to its central position shown in Figs. 9 and 19 is entirely automatic. Since the port 155 may not be in communication with the spiral groove 153 when the volume of delivery of the pump 64 should be automatically reduced, the automatic by-pass with the check valve 170 therein, is provided.

It will be evident that during normal control whether the valve 138 is rotated in one direction or the other, when swash plate has been adjusted to the desired position for a predetermined output volume of the pump 64, the swash plate will be automatically locked in adjusted position and held in locked position hydraulically until automatic reduction in volume output is effected by pressure overload after which any desired readjustment of the volume output of the pump may be effected by manually rotating the valve 138.

In the event that the electric cutting motor under the cover plate 19 is overloaded, provision is included in the system illustrated in the accompanying drawings to effect automatic decrease in the volume of oil delivered by the variable volume pump 64. When electrical overload occurs, the electro-magnetic valve 178 will be operated to effect automatically a decrease in the volume of oil delivered by the pump 64. The solenoid 179 is connected in the motor armature circuit so that when the electrical overload occurs the increased electric current through the motor armature will energize this solenoid sufficiently to cause it to pull down its plunger 180 against the action of the spring 181 which is located within the protective cap 182. This downward movement is relatively slow because of valve 184 connected to the chamber 183 in which the lower end of the plunger 180 is movable. When the solenoid is sufficiently de-energized the plunger 180 will be moved upwardly at a relatively rapid rate because then oil may be drawn into the chamber 183 freely past the check valve 184 as more fully hereinafter described.

Secured to the upper end of the plunger 180 are valves 186 and 187 connected by the rod 191. The valve 186 controls the connection between the ports 189 and 190. The rod 191 is of reduced diameter so that when the plunger 180 is in its upper position as shown in Fig. 15, the port 190 will be closed. When the plunger 180 is in its lower position, the valve 186 is in open position so that ports 189 and 190 will be in communication with each other.

A pipe 194 connects the port 190 of the electro-magnetic valve 178 to the port 195 of the three-core differential pressure control 119. Another pipe 192 connects the port 189 to the oil sump.

In the event of an electric overload on the electric driving motor, passageway 195 is vented and the hydraulic pressure on the lower side of the valve 121 in Fig. 18 will overcome the action of the spring 172. The hydraulic pressure will move the valve 121 to its uppermost position. When the plunger 180 of the electro-magnetic device is moved down in response to said electric overload the ports 189 and 190 are connected thereby venting the passageway 195 through the pipe 194 and the ports 189, 190 to the pipe 192 which leads to the oil sump.

When the electrical overload is spent, the plunger 180 will be moved by the spring 181 to its upper position shown in Fig. 15. This will move the valves 186 and 187 to their upper positions, cutting off communication of port 190 from port 189. This cuts off the venting from pipe 194 into pipe 192 but the latter will still be connected to the oil sump.

The electro-magnetic valve 178 is so arranged that electrical surges, such as may occur when starting the electric motor for driving the chain kerf-cutter, do not affect the control of the pump 64. This is accomplished by the differential action of the spring loaded ball 184 in the solenoid bleed-off valve mechanism shown in Fig. 15, this ball 184 being held slightly off its seat by an adjustable pin 202. The upper end of this pin 202 is provided with a screw-threaded enlargement 203 which is threaded into a screw-threaded opening in the upper side of the valve block 204. By inserting a screw driver in the slot 205 at the upper end of the enlargement 203 the pin 202 may be adjusted in elevation and thus the restricted opening at the ball 184 may be varied. Screw-threaded nuts 206 and 207 may be relied on to lock the pin 202 in adjusted position.

When the plunger 180 is moved down due to an electrical overload, the fluid, such as oil, displaced from beneath the plunger, flows through the restricted passageway between the ball 184 and its seat, thus slowing down the descending movement of the plunger 180. When the spring 181 moves the plunger 180 upwardly the fluid above the latter moves along the passageways 208, 209 and 210 and freely past the ball 184 into the passageways 211, 212 and 213, the spring 214 being compressed sufficiently to permit such free flow. This operation will permit the plunger 180 to be quickly restored to its upper position when the solenoid 179 is sufficiently de-energized.

Inasmuch as the solenoid 179 is always in the electric motor circuit, it is always energized but the electro-magnetic valve is so arranged that only when the electrical current through the solenoid 179 exceeds a certain predetermined number of amperes, will it have sufficient strength to pull down the plunger 180 against the action of the spring 181.

The electrical overload at which the electromagnetic valve 178 will act may be predetermined by adjustment of the initial compression of the spring 181. For this purpose a nut 215 may be screw-threaded onto the upper end of the valve rod 191 and provided with locking mechanism for holding the nut in adjusted position relative to the rod.

If desired, the lower end of the rod 191 may be provided with a circular head 216 located in a cylindrical recess in the coupling 217. The upper end of the plunger 180 may be provided with a circular head 218 also located in the cylindrical recess in the coupling 217. The coupling 217 may comprise split halves fitting in the upper end of the plunger or core opening in the block 219 of non-magnetic material.

The coupling arrangement between the plunger 180 and the rod 191 facilitates alignment of the valves 186 and 187 in their bores which prevents binding. Furthermore, the nut head 220 at the upper end of the screw 221 may be relied on to turn the latter in the nut 215 while the latter is held against turning. In this way the tension of the spring 181 may be adjusted and consequently the amperage necessary to cause the solenoid 179 to pull down its plunger 180 may be varied. The overload on the electric motor that will effect an automatic decrease in the delivery of oil from the pump 64 may thus be predetermined.

While the tendency is for the oil from the supercharging pump 67 to be by-passed through the branch pipes 81 and 84 (Fig. 32), the relief valve in the filter 82 and the relief valve 86 may be so set that such by-passing will not occur. Moreover, the closed circuit of the variable volume pump 64 handles a great deal more oil than the volume delivered by the supercharging pump 67. Consequently, under normal conditions of operation the entire volume from the supercharging pump is taken into the closed circuit of the pump 64 without any by-passing through the branch pipes 81 and 84 (Fig. 32). In the event of a pressure overload in the closed circuit of the pump 64, no oil may be needed from the supercharging pump and therefore the relief valve in the filter 82 and the relief valve 86 may be set to open automatically to by-pass the supercharging pump oil in co-operation with the automatic decrease of the volume of oil delivered into the closed circuit by the pump 64.

The hydraulic pressure from the supercharging pump 67 may be as low as 25 to 50 lbs. per square inch and the hydraulic pressure from the pump 64 may be as high as 750 to 1500 lbs. per square inch; but these figures are given merely by way of example and may be varied according to conditions of mining operations.

By referring to Figs. 3 and 4 it will be seen that whenever the electric driving motor under the plate 19 is operated, the shaft 37 will be rotated to drive the pump 64 but by releasing the clutch 28 no power need be transmitted to the cutter chain while on the transporting truck as shown in Fig. 27.

By actuating the rod 116 of the valve 107 the hydraulic motor 66 will be driven from the pump 64. The shaft of the motor 66 is splined to the shaft 291 as shown in Fig. 28. This shaft is the one which carries the worm 49 as shown in full lines in Fig. 7.

The shaft 291 is journaled to the support 292 by means of ball bearings as shown in Fig. 28. The support 292 is rigidly secured by welding, to the top of the partition plate 73.

Keyed to the shaft 291 is a pinion 293 which meshes with the spur gear 294. This spur gear is keyed to the inner end of the shaft 295. This shaft is journaled by means of the ball bearings 296 and 297. The ball bearing 296 is mounted on a cylindrical support 298 which is secured to the partition plate 73. The ball bearing 297 is mounted in the tubular support 299 secured to one of the side plates of the main frame of the mining machine. A tubular connector 300 is welded at its ends to the supports 298 and 299 and co-operates with the latter to form an enclosure for the shaft 295.

The outer portion of the support 299 flares outwardly as shown in Fig. 28, to receive within the same one element 301 of a coupling, the other element of which is located at 302 on the truck 290 shown in Fig. 27. When these coupling elements 301, 302 are connected by moving the mining machine onto the truck 290 into the position shown in Fig. 27, the starting of the electric driving motor of the mining machine will transmit power through the reduction gearing in the casting 303 to the truck propelling mechanism 304.

By reversing the electric driving motor the truck may be driven in either direction. When the truck is transported away from the place where the mining operations have been carried on, the cable reel 305 is driven in proper direction by the power transmission mechanism 306 to wind up the electric cable which connects the electric driving motor on the mining machine to the distant source of electric power.

When the mining machine shown in the accompanying drawings is supplied with the truck drive connections shown in Fig. 28, the piping diagram of Fig. 32 is modified by the insertion of the trammimg relief valve 307 shown in section in Fig. 26 and by the substitution of the relief valve mechanism 308 shown in Figs. 24 and 25 for the double check valve device shown in Fig. 20. The piping diagram as thus modified is shown in Fig. 31.

Figs. 24 and 25 are left-hand and right-hand sectional views of what may be termed a supercharging check valve and emergency relief valve combination. As stated above, this valve combination is useful in mining machines provided with the truck transportation driving mechanism shown in Fig. 28.

Under normal operations of the mining machine the flow of oil from the supercharging pump 67 through pipe 78 will be into the passageways 79' and 309, past the check valve 90' and through the passageway 310 and port 311 into the pipe 94.

Passageways 312, 313 connect pipe 98 with the chamber 314. Hydraulic pressure may thus be exerted on the right-hand end of the piston 315 as viewed in Fig. 24.

A chamber 316, a passageway 317 and a chamber 318 arranged in series, connect the pipe 94 to the space 319 back of the piston 320 which is in alignment with the piston 315. Sufficient hydraulic pressure either in chamber 314 or in chamber 318 will move one or both of the pistons 315, 320 against the valve 321 to the left as viewed in Fig. 24, thereby compressing the spring 322 and connecting the chambers 316 and 323 by moving the piston 324 out of the hole in which it fits. It will thus be seen that if the hydraulic pressure in either pipe 94 or pipe 98 becomes sufficiently great, the pump 64 will be short-circuited by the pipes 94 and 98.

The piping diagram illustrated in Fig. 31 is a

semi-closed hydraulic circuit in which the high pressure oil moves rapidly through the component parts and supercharged oil is introduced to maintain a sufficient supply of oil in the closed circuit and also to provide a surplus of oil so that heat may be taken from the closed circuit continuously. Such heat is generated by reason of high pressure leakage and mechanical inefficiency.

In the system illustrated in Fig. 31, if it be assumed that the mining machine is cutting from left to right, the supercharging oil is picked up from the selector valve 74 and delivered through pipe 75 to the supercharger pump 67 from which the oil is forced through the pipe 76 into filter 77. A portion of the oil branches from filter 77 through pipe 81 and secondary filter 82 to the top of the gummer shaft 25.

Due to a restriction in the secondary filter 82 the balance of the oil from filter 77 travels through line 78 to the supercharging check valve and emergency relief valve 308 shown in detail in Figs. 24 and 25. Since the high pressure oil in the closed system is being delivered to the valve mechanism 308, the supercharged oil enters the system through line 94, then traveling through line 95 to the variable volume pump 64.

From the variable volume pump 64 the oil travels through line 97 to the right-hand valve 101, through fluid pressure motor 65, returning to valve 101 and out into the line 106 and thence into chamber 325 of the trammimg relief valve 307 shown in detail in Fig. 26. In fact, the oil flows directly through the trammimg relief valve 307 into the left-hand valve 107 and through the latter to the left-hand motor 66 and then back into the left-hand valve 107 and out along line 114 and again through the trammimg relief valve 307 by way of its chamber 326 and finally joining the supercharged oil entering pipe 94.

During such flow of the oil from the supercharging pump 67, high pressure oil is being delivered from the right-hand valve 101 through line 117 to the three-core relief valve mechanism 119 and surplus low-pressure oil is leaving the left-hand valve 107 through line 122 into the three-core valve mechanism 119 and being delivered to the sprocket shaft 25, as shown in Figs. 18 and 31.

The trammimg relief valve 307 shown in Fig. 26 is similar in construction to the relief valve 308 but does not include the check valve 90' and its connections shown in Figs. 24 and 25. The trammimg relief valve 307 will come into operation when the left-hand fluid pressure motor 66 is operating the truck propelling mechanism 302, 304 while the mining machine is mounted on the transporting truck as shown in Fig. 27.

In the event that the operator should be trammimg the truck in one direction and then throw the valve handle 70 suddenly in the opposite direction, there would be a tendency to build up a very high overload hydraulic pressure because then the fluid pressure motor 66 would try to act as a pump and be pumping against the variable volume pump 64. This would occur even though the swash plate 69 was centered for zero volume delivery and the fluid pressure motor 66 acting as a pump would nevertheless overload the system.

The trammimg relief valve 307 may be so arranged as to operate only when the valve handle 70 is thus reversed. In such event, the abnormally high pressure in the pipe 106 acts through the passageways 312, 313' and chamber 314' on the upper end of the piston 315' to move

the latter down against the top of the valve 324' against the action of the spring 322' thereby opening the valve at 324' to connect the pipe 106 to the pipe 114, thus short-circuiting the fluid pressure motor 66 acting as a pump.

In a similar manner the motor 66 acting as a pump may be short-circuited when the pressure in the pipe 114 exceeds a predetermined maximum. The excessive hydraulic pressure is then exerted through the passageways 317, 318' onto the top of the piston 329'.

The combination check valve and relief valve combination 308 shown in Figs. 24 and 25 comes into play as a relief valve only when the truck 15 is being transported and the operator accidentally puts the right-hand motor 65 into operation while the cable drum 47 is still left in gear as shown in Fig. 5 and the anchoring hook at the free end of the retarding rope shown in Fig. 3 20 cannot be pulled past the adjacent direction sheaves 51, 55. In that event the right-hand motor 65 would tend to stall the hydraulic circuit flow instantly, causing an abnormal high pressure overload. When the truck is being transported, both the rope drums 47 and 48 should be moved out of gear by tilting each rope drum on its pivot 232 (Fig. 6) so as to throw the annular gear 46 out of mesh with the pinion 45. The rope drums may be held out of gear by letting the 30 plunger 236 (Fig. 6) snap into the recess 238 (Fig. 5).

It should also be noted that since the motors 65 and 66 are connected in series, regenerated power may be obtained from the motor 65 operating the payout drum during kerf-cutting operations. Whether kerf-cutting is taking place from right to left or left to right, the oil flowing in the hydraulic system always travels through the payout drum motor first, keeping this motor supercharged. Therefore if the payout rope becomes so taut that there is a cable pull on the payout drum during feeding operations along the mine bottom, the motor 65 feeds the machine against such pull on the payout rope to such an extent as to drive the motor 65 as a pump, thereby increasing the hydraulic pressure in the feeding or haulage motor 66. In other words, the driving of the motor 65 as a pump serves as a brake on the retarding rope. This hydraulic retarding arrangement, 50 due to the series arrangement of the motors 65 and 66, eliminates the use of mechanical brake bands which need continual adjustment and also eliminates the generation of heat due to friction of such mechanical brake bands. In 55 other words, either motor, 65 or 66, may be connected to the retarding rope drum while the other motor serves as the haulage or feeding motor for the feeding rope drum, and whichever motor is connected to the retarding rope drum serves as 60 an automatic brake under the control of its valve 101 or 107, because acting as a pump in series with the haulage motor.

Reverting to the automatic suction selector 74 shown in Fig. 17, it should be understood that the base 255 is secured to the mining machine frame and may be located in a depression in the bottom of the sump and provided with four intake or suction passageways, one of which is shown at 256 in Fig. 17. These passageways may be connected to 65 suction pipes which radiate forwardly, laterally and rearwardly so that at least one of them will receive oil whether the mining machine is tilted either forwardly or rearwardly or in either direction laterally.

75 On top of the base 255 is mounted a casing 257.

By means of four cap screws, one of which is shown in Fig. 17 at 258, the casing 275 may be secured to the base 255 in such position that four passageways 259 will register with four ports 260. There are four of such passageways 259 and four of such ports 260 each in fixed position relative to the base 255.

Journalized in the vertical tubular bearing 261 is a tubular pedestal 262 the lower end of which is pivoted by means of the ball bearing 263 on top of the base 255. A weight 264 is secured to and carried by the upper end of the pedestal 262. As the mining machine tilts, this weight swings to the lowest position it can find and thereby moves the port 265 in the tubular pedestal 262 into such position as to register with the port at the upper end of one of the passageways 259.

After the casing 257 has been secured to the base 255 by means of the cap screws 258, the cover plate 266 may be hermetically secured to such casing by means of the cap screws 266', to form a closed suction chamber 321.

It will thus be seen that the structure illustrated in Fig. 17 constitutes an automatic suction selector valve for automatically selecting the lowest part of the oil sump from which the oil is delivered to the hydraulic system regardless of the pitch or roll of the mining machine, while being fed over pitching and rolling mine bottoms.

Mechanism for indicating the delivery volume of the pump 64 is illustrated in Figs. 12, 13 and 14. The swash plate 69 carries an arcuate rack 267 with which meshes a pinion 268. The pinion 268 is secured to the inner end of the shaft 269 which is journaled in the bearing block 270. This bearing block may be detachably secured to the casing 136 by means of a cap screw, as shown in Fig. 12.

Secured to the outer end of the shaft 269 is a pointer 271 movable over a scale on the plate 272 as shown in Fig. 13. When the swash plate is centered as shown in Fig. 9, the pointer 271 should be at the designation indicating zero volume of pump delivery. When the swash plate is tilted to its maximum extent the pointer 271 will be moved clockwise, as viewed in Fig. 13, until it reaches the last designation on the scale.

The swash plate 69 may be provided with diametrically opposite extension pivot plates 273 each adapted to be journaled on a trunnion one of which is shown at 274 in the sectional plan view in Fig. 11. These trunnions are carried by supports one of which is shown at 275 in Fig. 11 fitting into a side opening in the casing 136 and secured to the latter by means of the cap screws 276. It will thus be seen that the swash plate 69 is tiltable on a horizontal transverse axis which lies in a horizontal plane intermediate the pivotal axes of the rollers 129, 129'.

Journalized in the ends of the casing 136 is a shaft 68 to which is keyed a cylinder block 277 having a plurality of cylinders 278 in which are adapted to reciprocate pistons 279 each of which is urged by means of springs (Fig. 9) to have its outer end impinge against the ring 280 mounted on the swash plate 69.

In the end plate 281 are two separate ports 282, 283 which are respectively in communication with the ports 284 and 285, as shown in Figs. 10 and 21. Of the ports 284, 285, one is the inlet and the other the outlet for the pump 64. The left-hand ends of the cylinders 278 are provided with arcuate ports 286 as shown in Figs. 9 and 22. The cylinder block 277 is driven by means of the electric driving motor, the connec-

tions for this purpose being shown in Figs. 3, 7 and 9.

Inasmuch as the valve unit shown in Fig. 18 may be located in the sump under the cover plate 5, 12, a drain outlet 287 may be provided for leakage past valve piston 124. Various supports may be provided as desired; for instance, the pump 64 and the hydraulic motors 65, 66 may be connected by a manifold 289 (Fig. 30) having therein the 10 necessary hydraulic passageways for these motors and the pump 64. Such manifold 289 may be supported in any desired manner. The purpose of providing such manifold is for that of making the structure as compact as possible and avoid leakage by the elimination of piping and fittings therefor.

By referring to Fig. 15 it will be seen that the various passageways and recesses are enclosed and may be filled with oil so that the dampening 20 action may be greater than with enclosed air. Furthermore, in case of sudden overloads on the electric driving motor the solenoid would not be able to pull the plunger 180 down and unload the hydraulic system instantly if oil is used in the 25 structure shown in Fig. 15. Moreover, the upper shoulder of the valve 186 and the lower shoulder of the valve 187 may be provided with circumferentially spaced V-slots similar to those shown at 200 in Fig. 18. With this arrangement, the 30 pipe 194 is gradually vented and the oil gradually bled into the pipe 192 to effect gradual shifting of the swash plate of the variable volume pump 64 toward central position. Upon an electric overload on the electric driving motor taking 35 place, there will result a gradual decrease of the volume of delivery from the pump 64 and this will take place automatically.

While the mining machine feeding mechanism shown in Fig. 3 is arranged for feeding the 40 machine from right to left, it should be understood that the rope 52 may be led between the direction pulleys 328, 329 and have its free end connected to an anchorage in the mine extraneous to the machine. The rope 52 then becomes the 45 retarding rope and the drum 48 becomes the retarding rope drum.

The rope 50 is then led from the drum 47 around the direction sheaves 330, 331 and its free 50 end connected to an anchorage extraneous to the machine. The drum 47 then becomes the feeding drum and the rope 50 becomes the feed 55 rope for feed of the mining machine from left to right along the coal face in shortwall kerf-cutting operations.

A general review of the normal and intended 60 operation of the shortwall kerf-cutting mining machine shown in Figs. 1, 2 and 3, will render clear the co-operation of the various elements during the kerf-cutting operations under different conditions. Fig. 31 illustrates the hydraulic circuit which is preferred for use with the truck 65 drive shown in Figs. 27 and 28, since Fig. 31 includes the tramming relief valve 307 and the supercharging valve and emergency relief valve combination shown at 308. Fig. 32, however, is preferred for use in the kerf-cutting mining machine when no truck drive is used, and in this view the valves 307 and 308 of Fig. 31 have been omitted and the valve 20 used instead.

In both Figs. 31 and 32 the hydraulic circuit is illustrated as semi-closed in which the high pressure oil moves rapidly through the component parts of the circuit, and supercharged oil is introduced to maintain a sufficient supply in 75 the preferred circuit by replacing that lost

through leakage and displacing from the circuit some of the oil which has become heated by the controlling operation of the mining machine during cutting of the coal in a coal vein.

Inasmuch as the kerf-cutting machine shown in Figs. 1, 2 and 3 is of the shortwall type, the cutter bar is rigid with the supporting framework which is adapted to rest on and slide over the mine bottom while the chain cutter cuts a kerf at the base of the mine vein.

By referring to Figs. 3, 7, 29 and 30, it will be seen that the hydraulic motor 65 is operatively connected to the rope drum 47 and the hydraulic motor 66 is operatively connected to the rope drum 48. The feed rope 52 is wound on the rope drum 48 and extends to an anchorage extraneous to the machine. The retarding rope 50 is wound on the rope drum 47 and extends to an anchorage extraneous to the machine. During the feeding of the kerf cutter, the main electric driving motor under the cover plate 19 drives the chain cutter 12 through the worm gearing 22, 23. This electric motor is preferably compound wound for constant speed and therefore the chain-cutter will be driven at the same speed for the various rates of feed.

Whenever the electric motor operates, the variable volume hydraulic pump 64 is operated. This pump 64 and the rotary hydraulic motors 65, 66 may each be of a multiple cylinder and swash plate type illustrated in Fig. 9, except that the swash plates of the motors 65, 66 may each be set to have a predetermined fixed inclination for constant volume at a given pressure. It should be particularly noted, however, that the motors 65 and 66 are connected in series and each is provided with a no-load by-pass so that these motors are operable individually and independently of each other by manual actuation of the handles 70, 71 shown in Fig. 2, so that either motor 65 or 66 may be started, stopped and reversed whenever desirable.

In further explanation of the purpose of the supercharger pump 67 in the hydraulic system shown in Figs. 31 and 32, it should be understood that the inclusion of the supercharger pump will enable the system to be operated with a minimum quantity of oil because the same oil may be used repeatedly at high speeds and high pressures in the semi-closed circuit. Since the supercharging pump 67 replenishes the circuit to compensate for leakage, and supplies a surplus of oil which may be bled from the circuit, overheating of any oil is prevented, thereby maintaining a substantially constant working temperature within the closed circuit. That is to say, by providing the supercharging pump 67 of relatively low capacity, relatively cool oil may be taken from the sump or left-hand compartment under the plate 72 as viewed in Fig. 7 and in Fig. 8, and supplied to the low pressure side of the closed circuit, to replace oil lost therefrom by leakage and also to displace the hot oil from the circuit back into the sump which serves as the source of supply.

The construction and arrangement illustrated diagrammatically in Figs. 31 and 32 are such that undue overloading of the electric driving motor is avoided, but maximum change in speed is obtained when the cutting is easy. The valve 138 is manually set in accordance with the hardness of the material to be cut and so that the rate of feed will be at a maximum without unduly overloading the electric driving motor. That is to

say, the rate of feed is kept at a maximum consistent with prevention of undue overloading.

The controlling means provided for the short-wall kerf-cutting mining machine is entirely hydraulic for hydraulic pressure overloads and also to provide the mining machine with controlling means which is electrical and hydraulic in combination for electric motor overloads. Such controlling means are provided for the purpose of 10 enabling the feed of the kerf-cutter to keep on operating continuously notwithstanding such overloads. The feed is automatically slowed down when harder coal than usual is encountered and then speeded up again automatically when such harder coal has been cut through, thereby preventing any stalling of the mining machine operations under varying conditions of hardness of the coal in the mine vein.

Consequently after the normal rate of feed is 20 predetermined by the setting of the valve 138 so that the feed will be at a maximum for the easiest kerf cutting, the operation is such that when coal of greater density is reached in the coal vein, the pressure in the hydraulic system will rise and 25 there will be an automatic decrease in the volume of delivery of the hydraulic liquid from the pump 64. When this takes place, the hydraulic motors 65 and 66 will be slowed down which results in a decrease in the rate of feed of the cutting mechanism. 30 When this emergency has been overcome, the operation will be automatic in restoring the pump 64 to its full volume of delivery, thereby again increasing the speed of feed in accordance with the setting of the valve 138.

35 When the rate of feed is decreased by decrease in volume of the hydraulic liquid from the pump 64, the electric motor may be overloaded to a limited extent, but in such event it is an increased pressure in the hydraulic system which effects an 40 automatic decrease in the rate of feed of the cutting mechanism. Only when the load on the electric motor exceeds a predetermined amount will the electro-magnetic valve mechanism 178 be operated by an excessive current flow through 45 the electric motor armature. The amount of permissible overload for the electric motor may be varied by adjustment of the tension in the spring 181 (Fig. 15).

50 Neither the slowing down of the feed due to pressure overload in the hydraulic circuit, nor the slowing down of the feed due to the electric motor overload, will interrupt the feeding operations, and in either such event when the overload has been spent the rate of feed will be automatically resumed and will continue in accordance with the setting of the valve 138.

Obviously those skilled in the art may make 55 various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

60 1. In a mining machine, the combination with a supporting frame, of cutting mechanism mounted thereon, a motor connected to said cutting mechanism to drive the same, a feeding rope drum, a retarding rope drum, a rotary hydraulic motor operatively connected to said feeding rope drum, an additional rotary hydraulic motor connected to said retarding rope drum and constructed to operate also as a pump, a hydraulic

25

system including a pump for supplying hydraulic pressure medium connecting said rotary hydraulic motors in series with each other and with said pump whereby the motor connected to the retarding rope may act as a pump to drive the other motor, and valve mechanism for controlling said hydraulic motors.

2. In a mining machine, the combination with a supporting frame, of cutting mechanism mounted thereon, a motor connected to said cutting mechanism to drive the same, feeding means for said cutting mechanism, means comprising two hydraulic motors for operating said feeding means, two controlling valves one for each of said hydraulic motors, a hydraulic pump, and hydraulic circuits and connections for placing said hydraulic motors in series through said controlling valves and enabling each controlling valve to control the stopping, starting and reversing of the hydraulic motor associated therewith independently of the stopping, starting and reversing of the other hydraulic motor.

3. In a hydraulic system for controlling the operation of a mining machine, the combination with a rotary pump, of hydraulic motor operated mechanism for varying the volume of delivery from said pump, said hydraulic motor operated mechanism comprising pistons of different diameters movable in separate chambers, a manually rotatable valve extending into the piston of smaller diameter to co-operate with a spiral groove therein connecting said chambers, and mechanism confining movement of said pistons along predetermined paths relative to said valve.

4. In apparatus of the class described, the combination with a variable volume fluid pressure pump, of motor operated means associated with said pump for varying the volume of delivery therefrom, a manually operable valve co-acting with said motor operated means for pre-determining the setting of the pump for a pre-determined normal volume of delivery at any one of a plurality of values between zero and its maximum delivery, a fluid pressure motor, and a fluid pressure system of control between said motor and said motor operated mechanism and adapted to operate automatically upon overload of fluid pressure in the system to cause said motor operated mechanism to effect a decrease in the volume of pressure supply from said pump entirely independently of its normal volume as determined by said manually operable valve.

5. In apparatus of the class described, the combination with a pump, of motor-operated mechanism for controlling the capacity of said pump, said motor-operated mechanism comprising a casing, a tubular guide extending from said casing, a piston in said casing, a hollow plunger carried by said piston and extending into said tubular guide, a rotary valve extending into said hollow plunger, and means comprising ports and passageways for controlling a fluid pressure medium in said casing and in said hollow plunger to effect movement of said piston in opposite directions.

6. In apparatus of the class described, the combination with a pump, of motor-operated mechanism for controlling the output of said pump, said motor-operated mechanism comprising a tubular piston closed at one end, a rotary valve extending into said tubular piston thereby forming two pressure chambers connected by a passageway extending along said valve, and means comprising ports and passageways for directing the fluid pressure medium into both

26

chambers when the output of the pump is to be varied or to direct such fluid pressure medium out of both chambers when the output of the pump is to be varied.

5. In a hydraulic system for controlling the operation of a mining machine, the combination with a rotary pump having a tiltable swash plate, of a fluid pressure motor for tilting said swash plate in one direction, another fluid pressure motor for tilting the swash plate in the opposite direction, and means for controlling said fluid pressure motors to cause either to retract when the other is expanded.

15. In a hydraulic system for controlling the operation of a mining machine, the combination with a rotary pump having a tiltable swash plate, of a fluid pressure motor for tilting said swash plate in one direction, another fluid pressure motor for tilting the swash plate in the opposite direction, connections between the supply port of said pump to both of said fluid pressure motors, an exhaust connection from one of said motors, and manually actuated valve mechanism associated with the motor having the exhaust connection for controlling the advance and retraction thereof against the action of the other motor and thereby adjust the tilting of the swash plate to vary the volume of delivery from said pump.

25. In apparatus of the class described, the combination with a variable volume pump comprising a swash plate, of a hydraulic motor acting on said swash plate to tilt it in one direction, another hydraulic motor to tilt said swash plate in the opposite direction, a manually rotatable valve for controlling one of said motors, and means comprising ports and passageways associated with said valve and said motors for operating the latter in opposite directions to adjust the tilting of said swash plate and thereby vary the capacity of said pump.

40. In apparatus of the class described, an electric motor, fluid pressure operated feeding means, a fluid pressure system of control for said fluid pressure operated feeding means comprising a variable volume pump driven by said motor, a bleed-off valve, an electro-magnet in circuit with said electric motor and connected to said bleed-off valve to open the same when the current through said electro-magnet exceeds a pre-determined amount due to excess current flow through said electric motor, and means operated by the opening of said bleed-off valve to effect reduction of fluid pressure in the said system by reducing the output from said pump.

45. In a mining machine comprising the combination with a supporting frame adapted to rest on and slide over a mine bottom, of kerf-cutting mechanism mounted on said supporting frame, a motor operatively connected to said kerf-cutting mechanism, a feed rope drum, a retarding rope drum, a fluid pressure motor for operating said feed rope drum, another fluid pressure motor for operating said retarding rope drum, a valve for starting said feed rope drum motor in either direction and for controlling the stopping of the same, another valve for starting the retarding rope drum motor in either direction and for stopping the same, and circuits and connections for connecting said motors in series when in operation

55. and for providing a no-load by-pass for each motor when its valve is in neutral position, the construction and arrangement being such that said motors shall be maintained in series whenever in operation and that when either motor is not operating its no-load by-pass shall be in

series with the other motor or its no-load by-pass.

12. In a mining machine, the combination with a supporting frame, of cutting mechanism mounted thereon, a motor connected to said cutting mechanism to drive the same, feeding means for said cutting mechanism, means comprising two reversible hydraulic rotary motors for operating said feeding means, a hydraulic system of supply of hydraulic pressure medium connecting said hydraulic motors in series with each other irrespective of the direction of rotation of either, a valve connected to one of said hydraulic motors for controlling the direction of rotation thereof, and another valve connected to the other motor to control the direction of rotation thereof, each valve being individual and each being operable independently of the other so that each hydraulic motor may be operated in either direction irrespective of the direction of rotation of the other but when operating said hydraulic motors shall always be connected in series with each other.

13. A system of control comprising a relatively high pressure hydraulic pump, a relatively low pressure hydraulic supercharging pump, piping connections between said supercharging pump and said high pressure pump including a pipe connected to the suction port thereof and a pipe connected to the supply port thereof, and two check valves one in each of said pipes, one check valve being adapted to open toward said suction port and the other check valve being adapted to open toward said supply port, the construction and arrangement being such that normally said supercharging pump replenishes fluid pressure medium through one of said check valves to the said suction port and that when the fluid pressure at the supply port falls below a predetermined value said supercharging pump acts through the other check valve to replenish fluid pressure medium in the supply line.

14. In apparatus of the class described, the combination with a variable volume fluid pressure pump comprising an adjustable member, of opposed reciprocating hydraulic motors associated with said member to adjust the same, means comprising a manually operable valve co-acting with one of said reciprocating hydraulic motors to predetermine the setting of said adjustable member for a predetermined volume of delivery of said pump, a fluid pressure motor, and a fluid pressure system of control comprising a relief valve adapted to operate automatically upon overload of fluid pressure in the system to cause said reciprocating hydraulic motors to automatically readjust said member to effect a decrease in the volume delivered by said pump until said overload has been spent and then automatically restore said member to its previously adjusted position corresponding to the setting of said manually operable valve.

15. In apparatus of the class described, the combination with a variable volume pump of relatively high capacity, of a supercharging pump of relatively low capacity, means for automatically varying the output from said first-named pump in accordance with variation of supply pressure therefrom, and a fluid pressure system of piping and connections comprising a double check valve between the supercharging pump and the supply and suction sides of said variable volume pump to cause said supercharging pump to automatically supply fluid pressure medium to either such supply or suction sides when the pressures therein fall below predetermined minimums.

16. In apparatus of the class described, the combination with a variable volume pump of relatively high capacity, of a supercharging pump of relatively low capacity, means operative upon gradual variation of supply pressure for automatically varying the volume of delivery from said first-named pump, emergency relief valve mechanism for short-circuiting said high-capacity pump upon sudden increase in supply pressure to a predetermined maximum, and means comprising a check valve for connecting said supercharging pump to the suction side of said high capacity pump, said check valve being adapted to open toward said suction side.

17. In apparatus of the class described, the combination with a variable volume pump, of a fluid pressure system therefor, a supercharging pump connected to said system to replenish fluid pressure medium escaping therefrom, differential pressure emergency relief valve mechanism adapted to short-circuit said first-named pump when the pressure therefrom exceeds a predetermined value, means for automatically varying the volume of delivery from said first-named pump in accordance with variation of pressure in said system, and means comprising a check valve for connecting said supercharging pump to said system to supply fluid pressure medium thereto when the pressure therein falls below a predetermined value.

18. In apparatus of the class described, the combination with a truck, of means for driving the same, including a reversible rotary hydraulic motor, valve mechanism for controlling the direction of rotation of said hydraulic motor, a rotary hydraulic pump for supplying fluid pressure medium to said rotary hydraulic motor, an emergency relief valve for automatically short-circuiting said pump when the pressure therefrom is excessive, and an additional emergency relief valve adapted to automatically short-circuit said hydraulic motor when said valve mechanism is so quickly reversed while the motor is driven as a pump by movement of said truck as to tend to build up an overload hydraulic pressure between said valve mechanism and said additional emergency relief valve mechanism, the construction and arrangement being such that when the pressures from said pump exceeds a predetermined value said first-named relief valve will automatically short-circuit said pump and when said valve mechanism is suddenly reversed and said rotary motor is driven as a pump in opposition to the aforesaid pump, the consequent overload hydraulic pressure will automatically operate said additional relief valve to short-circuit said rotary motor.

19. A power driven truck comprising a supporting frame, means including a rotary hydraulic motor for driving said truck, a variable volume pump connected to said hydraulic motor, a relief valve for short-circuiting said pump when the pressure thereof exceeds a predetermined value, reversing valve mechanism for said rotary hydraulic motor, an additional relief valve, and a hydraulic system of piping and connections to effect the operation of said additional relief valve to short-circuit said rotary hydraulic motor when said reversing valve mechanism is operated in an attempt to suddenly reverse said hydraulic motor during rotation while connected to said feeding means.

20. In apparatus of the class described, the combination with a mining machine comprising a hydraulic motor, of a truck for carrying and

transporting said mining machine from place to place, power transmission mechanism on said truck to propel the latter, mechanism for coupling said hydraulic motor to said truck propelling mechanism, a hydraulic system of control for enabling said hydraulic motor to operate said propelling mechanism, said system including a pump for supplying fluid pressure medium to said hydraulic motor, an emergency relief valve for automatically short-circuiting said pump when the pressure therefrom exceeds a predetermined value, and an additional emergency relief valve for short-circuiting said hydraulic motor upon sudden overload thereon.

21. In a mining machine, the combination with a supporting frame adapted to rest on and slide over a mine bottom, of cutting mechanism mounted thereon, a motor connected to said cutting mechanism to drive the same, a feeding rope drum, a retarding rope drum, ropes connected to and wound on said rope drums and adapted to have their free ends connected to anchorages in the mine extraneous to the machine, a rotary hydraulic motor connected to said feeding rope drum, another rotary hydraulic motor connected to said retarding rope drum, a hydraulic system of control connecting said hydraulic motors in series, and means in such system for individually controlling said motors to cause the hydraulic motor connected to the retarding rope drum to act as a pump and thereby serve as a brake to keep the retarding rope taut as it is being paid out from said retarding rope drum.

22. In apparatus of the class described, the combination with a variable volume pump, of an electric motor for driving said pump, hydraulically operated motor means for adjusting the volume of delivery from said pump, means comprising a differential valve for controlling said adjusting means, and an electro-magnetic valve operating in response to overload of said electric motor for controlling said differential valve.

23. In apparatus of the class described, the combination with a variable volume pump, of hydraulic motor operated means for regulating the volume of delivery from said pump, a differential valve, a low pressure hydraulic conduit connection to one end of said valve, a high pressure hydraulic conduit connection between the supply side of said pump and the other end of said valve, a low pressure relief valve, and means for automatically operating said differential valve to connect said supply side through said relief valve to exhaust when the pressure in said supply side falls below a predetermined value and automatically restoring said valve to initial position when the pressure in said supply side is restored to normal.

24. In apparatus of the class described, the combination with a main pump in a closed circuit, of a differential valve, a branch conduit connecting the supply side of said pump to one end of said valve, another branch conduit connecting the suction side of said pump to the other end of said valve, a low pressure relief valve in a connection between said second-named branch conduit and exhaust, a port in said differential valve for connecting said first-named branch conduit through said relief valve to exhaust when the pressure in the supply side of said pump falls below a predetermined value, an auxiliary pump, and means for automatically connecting said auxiliary pump in parallel with said main pump when the pressure in said supply conduit falls below a predetermined value as aforesaid, the construc-

tion and arrangement being such that while said pumps are connected in parallel the supply liquid through said first-named branch conduit flows to exhaust and when the pressure in said supply side is restored to normal the pumps are connected in series and the liquid from said main pump circulates in said closed circuit said differential valve then being in initial position to cut off the aforesaid flow to exhaust.

25. In apparatus of the class described, the combination with a pump, of hydraulic motor operated means for controlling the output from said pump, a differential valve connected at one end to the supply side of said pump, a source of low pressure supply, a connection between said source of low pressure supply and the other end of said valve, means co-acting with said valve to cut off the supply side of said pump from said hydraulic motor operated controlling means when the pressure in said supply side falls below a predetermined value, and a port in said valve for connecting said supply side of said pump through the interior of said valve to exhaust to effect replenishment of hydraulic pressure medium and restoration of the pressure in said supply side whereupon said supply side shall again be connected to said hydraulic motor operated controlling means and said port cut off from exhaust.

26. In apparatus of the class described, the combination with a variable volume pump, of hydraulic motor operated means for regulating the volume of delivery from said pump, a spring-loaded valve having a restricted opening between the ends thereof, a high-pressure by-pass relief valve connected to one end of said spring-loaded valve, and ports and passageways associated with said first-named valve and connecting said pump to said regulating means to effect decrease in volume delivery from said pump when the supply pressure becomes sufficient to move said first-named valve against the action of its spring and said relief valve is opened, said restricted opening serving to restore said valve to its initial position by retarded movement of liquid therethrough and re-establishment of equilibrium.

27. In apparatus of the class described, the combination with a variable volume pump, of hydraulic motor operated means for regulating the volume of delivery from said pump, a pilot valve having a restricted passageway between its ends, a spring acting on said valve to normally hold it in initial position, ports and passageways associated with said valve to connect said pump to said regulating means when the valve is in its initial position, means affording a closed chamber for that end of the valve with which the spring is associated, an additional valve adapted to be opened to release liquid from said closed chamber when the pressure therein becomes excessive, and additional ports and passageways connecting said first-named valve to said regulating means to effect decrease in the output from said pump when liquid is released from said closed chamber as aforesaid, the construction and arrangement being such that said restricted opening will permit said spring to restore the first-named valve to its initial position upon sufficient drop in hydraulic pressure on that end of said first-named valve remote from the said spring.

28. In apparatus of the class described, the combination with a variable volume pump, of hydraulic motor operated means for regulating the volume of delivery from said pump, a connection between said pump and said regulating means, a 75 pilot valve for controlling said connection, an ad-

ditional connection between said valve and said regulating means, a check valve in said additional connection, and means for effecting automatic operation of both of said valves to cause a flow through said additional connection and the operation of said regulating means to decrease the output from said pump.

FLORENCE H. C. JEFFREY,
Executrix of the Estate of Robert K. Jeffrey, Deceased.
